INVENTOR.
Adolph A. Pochyla,
BY *Geo. F. Kimmel.*
ATTORNEY.

UNITED STATES PATENT OFFICE

ADOLPH A. POCHYLA, OF MCGREGOR, TEXAS

LEMON SQUEEZER

Application filed June 4, 1930. Serial No. 459,243.

This invention relates to a lemon squeezer particularly adapted for use in squeezing the juice from a portion of a lemon into an ice tea glass, and has for its primary object to provide, in a manner as hereinafter set forth, a device of such character by means of which the desired result may be accomplished without the necessity of touching the lemon with the fingers, and without likelihood of any deposit of lemon juice outside of the glass.

A further object of the invention is to provide a device for the purpose aforesaid which is of neat and compact construction, and which may be plated in the same manner as ordinary silverware, in order that the device may present an attractive appearance when associated with a glass.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the several views:

Figure 1 is an elevation of a lemon squeezer in accordance with this invention showing the same in association with a drinking glass.

Figure 2 is an elevation of the lemon squeezer shown in a position at a right angle to that shown in Figure 1.

Figure 3 is a vertical section through the lemon squeezer.

Figure 4 is a section taken on line 4—4 of Figure 3.

Figure 5 is a section taken on line 5—5 of Figure 3.

Referring to the drawings in detail, the numeral 1 designates a spoon element of concave formation which is adapted to have deposited therein a portion of a lemon, such as indicated at 2. Formed on the spoon element 1 is a handle 3 which extends substantially

at a right angle to the spoon element 1 and an upward end portion of which is curved to provide a split loop 4, the extreme end portion of which is bent outwardly and extends at an angle to the plane of the handle 3. 55 The angularly disposed outer end portion of the loop 4 is indicated at 5 and the line of emergence between the same and the loop 4 provides a rounded surface 6 for bearing against the outer face of a glass, such as 7, 60 when the loop 4 is engaged with the rim of the glass with the spoon element 1 disposed within the glass.

Encircling the handle 3, adjacent the split loop 4, is a loop element 8 of rectangular contour which is formed with or fixedly secured to the rearward face of the handle 3. The loop element 8 projects from the forward face of the handle 3 and has slidably extended therethrough the handle 9 of a movable spoon element 10 similar to the spoon element 1. The handles 9 and 3 extend in parallel contacting relation with the spoon element 10 disposed directly over the spoon element 1. Formed integrally with the handle 75 9, adjacent the spoon element 10, are a pair of lateral projections which are bent to have their outer end portions extend in contacting parallel relation to the rearward face of the handle 3. The projections 11, in connection 80 with the handle 9, provide a split loop 12 of rectangular contour which slidably embraces the handle 3.

Toward the free end thereof, the handle 9 merges into a portion 13 which is disposed 85 at an angle of substantially 45° to the handle 9 and which merges in a horizontally disposed portion 14 formed with a return portion 15.

In the use of my improved lemon squeezer, 90 the same is preferably positioned with respect to a glass as shown in Figure 1, with the split loop 4 projecting from the opposite side of the glass to the position of the user of the glass. In the operation of the squeezer, 95 the middle finger of the user is inserted through the split loop 4, the index finger of the user is positioned between the split loop 4 and horizontal portion 14 of the handle 9, and the thumb of the user is positioned 100

against the upper face of the portion 14. The thumb is then pressed toward the fingers which causes a sliding movement of the handle 9 whereby the spoon 10 is moved toward the spoon 1. The spoons 1 and 10 are provided with spaced slots 16 in order that the juice from the lemon 2 may readily escape from the spoons. Preferably the spoons 1 and 10 are positioned beneath the level of the liquid within the glass in order that there may be no possibility of any of the juice from the lemon escaping over the upper edge of the glass.

If desired the squeezer may be positioned 15 on the glass with the spoons 1 and 10 located outside of the glass and with the split loop 4 located inside of the glass. When the squeezer is positioned in such a manner, the same is located on the side of the glass next 20 to the user in order to be in proper position for engagement by the fingers and thumb of the user.

Owing to the manner in which the squeezer is grasped by the thumb and fingers of the 25 user, the handle member may be formed of relatively light material without likelihood of bending the slidable handle 9, as such handle member is supported during the use of the squeezer by the index finger of the 30 user. The device may be formed of any suitable material customarily used in the construction of silverware, and may be plated or otherwise finished to conform with other articles of silver with which the same is used.

35 It is thought that the many advantages of a lemon squeezer in accordance with this invention will be readily apparent, and although the preferred embodiment of the invention is as illustrated and described, it is 40 to be understood that changes in the details of construction may be resorted to, so long as such changes fall within the scope of the invention as defined in the appended claims.

What I claim is:

45 1. A lemon squeezer adapted for use in connection with a drinking glass and comprising, a pair of relatively movable spoon elements adapted to have a portion of lemon placed therebetween, a pair of handle members 50 for the spoon elements extending in parallel relation, and means for slidably connecting the handle members together, one of said handle members having an end portion thereof bent into the form of a split loop 55 for receiving an edge portion of the glass therein and for receiving a finger of the user when operating the squeezer.

60 2. A lemon squeezer adapted for use in connection with a drinking glass and comprising, a pair of relatively movable spoon elements adapted to have a portion of lemon placed therebetween, a pair of handle members 65 for the spoon elements extending in parallel relation, and means for slidably connecting the handle members together, one

of said handle members having an end portion thereof bent into the form of a split loop for receiving an edge portion of the glass therein, the other of said handle members having an end portion disposed at a 70 right angle thereto and extending in spaced, superposed relation with respect to said split loop.

3. A lemon squeezer comprising, a pair of relatively movable spoon elements adapted 75 to have a portion of lemon placed therebetween, and a pair of relatively thin handle members for the spoon elements, said handle members extending in parallel relation and each having a relatively wide loop slidably 80 embracing the other.

In testimony whereof, I affix my signature hereto.

ADOLPH A. POCHYLA.
